RADIO SIGNALING SYSTEM

Gaston Adelin Mathieu, London, England, assignee to Radio Corporation of America, a corporation of Delaware

Application October 25, 1928, Serial No. 314,885,
and in Great Britain November 9, 1927

13 Claims. (Cl. 250—9)

This invention relates to radio and the like high frequency receiving systems, and more particularly to multiple heterodyne receivers—i. e. receivers incorporating a plurality of heterodynes—suitable for use in receiving continuous waves modulated at a plurality of frequencies or frequency ranges or any combination thereof for the purpose of providing a plurality of communication channels.

10. In receivers comprising a plurality of heterodynes, and involving the use of band filter amplifiers required for the simultaneous amplification of several frequencies tuning becomes a matter of considerable difficulty, owing to the extreme degree of accuracy to which the local oscillators must be adjusted and owing to the necessity of their frequencies maintaining a fixed relationship, in order that the signal frequencies may be maintained centered on the band filter amplifiers.

20. According to this invention a multiple heterodyne receiver comprises a plurality of heterodynes whereby, for correct reception, the same frequency is obtained at different parts of the receiver, means for feeding the said frequencies into a common control circuit, and means for adjusting one or more of said heterodynes, whereby a zero or nil beat may be obtained in said common control circuit.

30. The invention is illustrated in the accompanying drawings, in which,

Fig. 1 shows schematically one form of receiver suitable for use to receive a carrier wave modulated by three different signals, two of the modulations being telegraph modulations, and the third a telephone modulation; and,

Fig. 2 illustrates coupling apparatus utilized in Fig. 1; and,

Fig. 3 is a modification of the receiver illustrated in Fig. 1.

40. It is to be understood, of course, that the invention is not limited to the particular applications illustrated and that the numerical values given in the following description are only by way of example.

The signals to be received by the receiver shown in Fig. 1, for example, comprise a telephone channel, say, 2000 cycles wide (between, say 400 and 2400 cycles), a 7000 cycle telegraph channel, and a 9000 cycle telegraph channel,

modulated upon a carrier wave of 20000 kilocycles, and it is assumed that the only wave bands radiated by the transmitter are:

(a) The carrier—20,000 kilocycles.

(b) The telephone band, 20,000 kilocycles $\pm$ 55 the telephone frequency band.

(c) The first telegraph band, 20,000 kilocycles $\pm$ 7,000 cycles.

(d) The second telegraph band, 20,000 kilocycles $\pm$ 9000 cycles.

50. Referring to Fig. 1 of the accompanying drawings, all the frequencies are received upon an aerial N and passed through a sharply tuned high frequency circuit T whose cut-off is such that any wave whose frequency is more than 180,000 cycles greater than the carrier frequency (20,000 kilocycles) is eliminated. The modulated carrier from the output side of the tuned circuit is now changed to a modulated carrier of 180,000 cycles, by means of a first heterodyne H1, supplying 60 19,820 kilocycles, and modulated valves M1; the new modulated carrier being then amplified in a multi-stage filter amplifier A1 having a sharp lower cut-off at 170,000 cycles, and a sharp upper cut-off at 190,000 cycles, and so designed as to 65 avoid any rectification.

70. The last stage of this amplifier comprises coupling valves CV1, CV2, whose grid-anode capacities are very carefully neutralized, and which are associated with sharply tuned circuits, whereby the band of frequencies occupied by the telephone channel (which band lies in the middle of the whole band of the amplifier) is separated out from the said whole band of the amplifier.

75. This frequency selective apparatus is illustrated in conventional diagrammatic form in Fig. 2 of the drawings which is self-explanatory. In Fig. 2, A represents the output of cut-off A. (Fig. 1) B represents the output of CV2 (Fig. 1) and C represents the output of CV1 (Fig. 1).

80. The whole frequency band of 170,000–190,000 cycles is fed in at A and fed out at B (see Fig. 2), the central telephone band being fed out at C whence it is passed through a filter F1 (see Fig. 1) whose cut-off points are arranged to pass only 85 those frequencies covered by the telephone modulated carrier. It is then rectified and amplified in a direct current amplifier D1, passed through an automatic gain regulator, such as that described in my copending U. S. application, Serial 100

No. 239,843, filed Dec. 14, 1927, and indicated at AGC and A2, re-amplified at A3 and transmitted down a land-line or utilized in any other way. It will be noted that the telephone channel is separated out prior to rectification, an arrangement which, in conjunction with the telephone filter, substantially eliminates the "key-clicks" of the telegraph transmission from the telephone channel.

10 The output from line B (see Fig. 2) is subjected to the action of a second heterodyne H2 supplying 150,000 cycles (see Fig. 1) and modulators M2, whereby the carrier frequency is changed to a frequency of 30,000 cycles and this 15 new carrier is eliminated by a filter F2 having an "infinite" impedance to 30,000 cycles per second. This carrier elimination is effected for the following reasons:—

1. The carrier wave is much more powerful 20 than any of the modulating waves and consequently any attempt to secure a further large amplification of all the modulated waves separately or as a unit without suppressing the carrier, would prove a very difficult matter if saturation and rectification are to be carefully avoided 25 as is the case.

2. Because in the use of short waves it has been found that with a modulation of 5000 cycles and upwards, the difference in time for fading 30 for the carrier and the two side waves begins to be sufficiently marked to make use of this phenomenon considerably to reduce the consequence of fading, first by using the side waves separately and secondly by eliminating the variable carrier and resupplying it later at a constant 35 amplitude.

The modulated signals having the carrier suppressed are now passed through a pair of parallel filters F3, F4 one of which is a high pass and 40 the other a low pass filter, designed to separate the upper and lower modulation side bands and to attenuate strongly the telephone frequencies. The low pass filter admits only frequencies below 26,000 cycles and the high pass filter admits 45 only frequencies above 34,000 cycles per second. The side bands are thus separated in order to obtain the advantage of the frequently observed time differences in fading which occurs between them. It is obvious that the high and low pass filters can be replaced by suitable band filters. 50

The outputs from the filters F3, F4 are now passed through multi-stage band filter amplifiers A4, A5, designed each to admit a frequency band 4000 cycles wide on a central frequency in one case 8,000 cycles above, and in the other 55 8,000 cycles below 30,000 cycles, (8,000 cycles is of course, the central frequency between the two telegraph frequencies). The outputs from these band filter amplifiers operate into remodulators 60 R1, R2, whereby the suppressed carrier is resupplied at constant amplitude by a local generator G operating through coupling valves CV3, CV4. This local generator, and the second heterodyne whereby a carrier frequency of 30,000 65 cycles was first obtained, must be of as constant frequency and as pure and free from harmonics as possible. Preferably each is governed by means of a known neon tube indicating wavemeter or similar device (indicated at W1 and W2), 70 whereby their frequencies may be adjusted and maintained within 50 cycles of the required value—a degree of accuracy which is amply sufficient.

The outputs from the remodulators, which deal 75 each with one side band, are now passed through

pairs F5, F6, F5', F6', of parallel filters, one filter of each pair being adapted to pass 7000 cycles $\pm$ 500 cycles (the allowance made for variation in the original radio-transmitted carrier), the other being designed to pass 9000 cycles $\pm$ 500 cycles. The now separated telegraph frequencies are rectified at D2, D3 and D4, D5, and the direct current components of the corresponding frequencies passed through limiting valves L1 80 V1, L2 V2, and suitable telegraph bridges B1 B2 to be retransmitted in any desired way. 85

It is also possible to join the direct current output component of the upper and lower side bands of each of the telegraph channels and to combine their effect into the same limiting valve 90 and telegraph bridges instead of recording them separately.

In the case where the time constant is found to be slightly different for the signals originating from the output of the upper and lower side bands, the required correction of time can be obtained by the use of a delay circuit introduced either in the high or the low frequency of one 95 of the telegraph detectors. Such delay circuits are indicated at x.

The local generator G is also arranged to feed (preferably through coupling valve CV5) a detector controlling circuit M3 (preferably of the push-pull type) whose input circuit is also fed as shown from one or all of the trap circuits 100 involved in the construction of the filter F2 designed for the suppression of the 30,000 cycle carrier.

It will be seen that the simultaneous action on the said controlling detector M3 of the carrier, and the 30,000 cycle wave of the local generator, will produce a beat note in the output of the detector, the said beat being zero when the original carrier is changed exactly to 30,000 cycles, by the action of the first and second heterodynes. This beat is amplified at A6 and fed to a loudspeaker or indicating instrument Z.

In practice the local generator G and the second heterodyne H2 may be adjusted to be substantially constant and the latter can be maintained adjusted to the correct wave length to produce a beat of 30,000 cycles, so long as the first heterodyne changes the original carrier to 180,000 cycles—the middle frequency of the first band amplifier—so that adjustment is reduced to 125 that of the first heterodyne.

It is obvious that any variation from the original adjustment will alter the zero beat note at A6 into an acoustic one (due either to variation in the frequency of the carrier at the transmitting station or to the variation of the heterodynes of the receiving station) whose frequency will indicate in cycles the amount of the variation.

To prevent the speech frequency appearing in 135 the output of the said controlling valve, a low-pass filter with a sharp cut-off of 500 cycles is incorporated in connection with M3.

The output of this filter may be amplified, as stated above, by the low frequency amplifier A6 140 working into a loud speaker which will only be silent for the zero point of adjustment. Moreover, if desired, there may be inserted in the output circuit of the amplifier A6 sensitive relays tuned to say 250, 350 and 450 cycles, and adapted to light lamps of different colors. Such relays are indicated at 1, 2 and 3 in Fig. 3, the lamps being indicated by numerals 4, 5 and 6.

In a modification of the above described arrangement, a harmonic of the generator G is uti- 150

lized as the second heterodyne H2, and thereby the installation is rendered still more convenient to control and satisfactory to use. For example, if the middle band frequency of the amplifier A1 is chosen at 181,998 cycles, and the carrier frequency to be suppressed at F2 and re-supplied at R1, R2 is 30,333 cycles, the seventh harmonic of the frequency generated at G (i. e. 212,331 cycles) will be the correct frequency to be supplied at M2.

This arrangement is also shown in Fig. 3 where G is the harmonic generator and 7 and 8 are filters for passing respectively 30,333 cycles and 181,998 cycles.

15 Where a plurality of receivers in accordance with this invention are to be located close to one another, for example, in the same room—a preferred arrangement is to employ a common master generator (G) for all the receivers a harmonic 20 of the output of the said generator being employed as a master second heterodyne (H2) for all the receivers. This arrangement avoids much interference which might otherwise occur from undesired beats.

25 A harmonic frequency may be obtained from the generator G in any desired manner. The following method has, however, been found suitable in practice:—

The fundamental frequency is generated by a 30 valve circuit and flows in an oscillatory circuit comprising a condenser shunted by an inductance.

Owing to the fact that the impedance of the 35 condenser to harmonic frequency is much less than the impedance of the inductance, a larger current of the harmonic frequency will flow in the condenser branch, and by coupling a coil to a small inductance in this branch, the current of harmonic frequency can be obtained and applied in a tuned amplifier to raise its amplitude 40 to a suitable value.

It will be seen that controlling arrangements as herein described secure:—

(1) A very simple means of tuning a multiplex 45 receiver which would otherwise be intricate.

(2) An instantaneous indicator for all variation occurring or needed at the receiver.

It will be realized that the controlling device (providing the local generator is free from undesired harmonics) cannot introduce any perturbation in the telephone channel working on 50 180,000 plus or minus 2500 cycles.

Having now particularly described and ascertained the nature of my said invention and in 55 what manner the same is to be performed, I declare that what I claim is:—

1. The method of signaling utilizing the reception of a carrier wave modulated by a plurality of signals, which includes reducing the frequency 60 of the carrier of all of the signals, separating the side bands of the reduced carrier, detecting side bands of the reduced carrier caused by one of the signals, and still further reducing the carrier frequency of other of said signals, filtering out the last utilized carrier, amplifying the side bands 65 of said last utilized carrier and resupplying the carrier to the amplified side bands.

2. The method of signaling utilizing the reception of a carrier wave modulated by a plurality 70 of signals, which includes reducing the frequency of the carrier of all of the signals, separating the side bands of the reduced carrier, detecting side bands of the reduced carrier caused by one of the signals, and still further reducing the carrier frequency of other of said signals, isolating the

last utilized carrier, amplifying the side bands of said last utilized carrier, generating a constant amplitude carrier, supplying the generated carrier to the amplified side bands, and combining the generated carrier and the isolated carrier.

3. The method of signaling utilizing the reception of a carrier modulated by a plurality of signals which includes filtering the received carrier so as to pass substantially the frequencies covered by the modulated carrier, reducing the carrier frequency, separating a band of frequencies caused by one of the signals from the reduced modulated carrier, further reducing the carrier frequency of the other signals, shunting out the further reduced carrier, resupplying a carrier to the side bands and combining the shunted out carrier and the resupplied carrier.

4. In combination, in a radio receiver adapted for the carrier wave modulated by a plurality of signals, which includes means for reducing the frequency of the carrier of all of the signals, means for separating the side bands of the reduced carrier, means for detecting side bands of the reduced carrier caused by one of the signals, means for still further reducing the carrier frequency of other of said signals, means for eliminating the last utilized carrier, means for amplifying side bands of said last utilized carrier and means for resupplying a carrier to the amplified side bands.

5. In combination, in a radio receiver adapted for receiving a carrier modulated by a plurality of signals, means for reducing the frequency of the carrier of all the signals, means for separating the side bands of the reduced carrier, means for detecting side bands of the reduced carrier caused by one of the signals, and means for still further reducing the carrier frequency of other of said signals, means for isolating the last utilized carrier, means for amplifying the side bands 110 of said last utilized carrier, a generator for generating a constant amplitude carrier, means for supplying the generated carrier to the amplified side bands, and means for beating together the generated and the isolated carrier.

6. In combination, a filter for passing substantially all of the frequencies covered by modulating a carrier by a plurality of signals, heterodyning means for reducing the carrier frequency, means for separating a band of frequencies caused by one of the signals from the reduced modulated carrier, other heterodyning means for further reducing the carrier frequency of the other signals, means for shunting out the further reduced carrier, means for separating and amplifying the side bands of the carrier which has been shunted out, means for generating a carrier, and means for combining the generated carrier and the carrier which has been shunted out to produce a beat note.

7. The method of signaling, utilizing the reception of a carrier wave modulated by a plurality of signals, which includes reducing the frequency of the carrier of all of the signals; separating out certain of the side bands of the reduced carrier and detecting said side bands for deriving therefrom certain of the signals and still further reducing the carrier frequency of the other of said signals.

8. In a system for receiving a carrier wave modulated by a plurality of frequency bands, means for receiving said carrier wave, a band filtering device adapted to pass substantially only the band of frequencies covered by the modulated carrier, a first heterodyne adapted to reduce the
